AIRPLANE STEP STRUCTURE

Lewis E. Reisner, Bellemead, and Ora G. Blocher, Donelson, Tenn., assignors, by mesne assignments, to Vultee Aircraft, Inc., a corporation of Delaware

Application October 7, 1940, Serial No. 360,044

6 Claims. (Cl. 244—117)

The present invention relates generally to ladder structures. More particularly the invention relates to that type of ladder structure which is associated with, and forms a part of, the fuselage of an airplane and comprises a pair of similarly shaped ladders which are disposed at opposite sides of the fuselage and beneath the fuselage side doors and serve as a medium for permitting the persons using the airplane to ascend in connection with boarding of the airplane and also as a medium for permitting such persons to descend to the ground when leaving the airplane.

One object of the invention is to provide an airplane ladder structure of this type which is generally an improvement upon, and has certain inherent advantages over, previously designed structures of the same general character.

Another object of the invention is to provide a ladder structure of the type under consideration in which the two ladders are mounted to swing back and forth between an inoperative or out of the way position under the fuselage and an operative position wherein they are extended.

Another object of the invention is to provide an airplane ladder structure of the last mentioned type and character in which the ladders when in their inoperative or out of the way position, fit within ladder shaped pockets in the bottom portion of the airplane fuselage and thus aerodynamic drag, as far as the airplane is concerned, is reduced to a minimum.

Another object of the invention is to provide an airplane ladder structure of the type and character under consideration which comprises in addition to the two ladders, simple and novel means for conjointly shifting the ladders back and forth between their inoperative and operative positions.

A further object of the invention is to provide a ladder structure of the last mentioned character in which the ladder shifting means includes a control element in the interior of the airplane fuselage and is so designed and constructed that the ladders when in their extended or operative position are locked against inward swinging movement except by manipulation or shift of the control element.

A still further object of the invention is to provide an airplane ladder structure which efficiently and effectively fulfills its intended purpose and not only may be constructed at a comparatively low cost but also is light in weight as well as durable.

Other objects of the invention and the various advantages and characteristics of the present

airplane ladder structure will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a fragmentary side view of an airplane having applied thereto a ladder structure embodying the invention, parts of the fuselage of the airplane being broken away and other parts being shown in section for purposes of illustration;

Figure 2 is an enlarged vertical transverse section taken on the line 2—2 of Figure 1 and illustrating the ladders in their extended or operative position;

Figure 3 is a fragmentary bottom view of the airplane showing the ladders in their retracted or inoperative position;

Figure 4 is a large scale vertical transverse section illustrating in detail the construction and design of the means for conjointly shifting or swinging the ladders back and forth between their operative and inoperative positions;

Figure 5 is a fragmentary horizontal section on the line 5—5 of Figure 4; and

Figure 6 is an enlarged section on the line 6—6 of Figure 4.

The ladder structure which is shown in the drawings constitutes the preferred embodiment of the invention. It is disclosed in connection with, and forms a part of an airplane A and comprises a pair of ladders 7. The airplane A is of standard or conventional design and embodies a fuselage a, a landing gear a¹, an engine driven propellor a² and a wing structure a³. The fuselage a has the landing gear and wing structure affixed to it and carries the propellor a² and the engine for driving the propellor at the front end thereof. It has an empennage (not shown) at its rear end and embodies in the central portion thereof a combined pilot and passenger compartment a⁴. This compartment embodies a pilot seat a⁵ in the front portion and a passenger seat a⁶ in its rear portion. Two opposed similarly shaped doorways a⁷ in the sides of the fuselage permit persons using the airplane to enter and leave the compartment a⁴. These two doorways are normally closed by a pair of doors a⁸ and these are hinged at the front thereof so that they

may be swung outwards into an open position. The fuselage *a* of the airplane *A* embodies a floorboard *a*⁹ for the compartment *a*⁴, and consists of a framework *a*¹⁰ and a skin *a*¹¹ around the framework. The framework includes at the bottom thereof a pair of laterally spaced longerons *a*¹² and these are cross connected by a cross member *a*¹³. The longerons *a*¹² are of tubular design and are disposed beneath the floorboard *a*⁹. The cross member *a*¹³ is also of tubular design and is located directly in front of the passenger seat *a*⁶. The bottom portion of the skin *a*¹¹ of the fuselage *a* is transversely rounded or curved, as shown in Figure 4.

The ladders *1* of the ladder structure are located on opposite sides of the fuselage *a*, as shown in Figure 2, and are positioned directly beneath the doorways *a*⁷. They are substantially the same in size and shape and each consists of a front side member *8*, a rear side member *9* and a pair of vertically spaced rungs *10*. The side members and rungs of the ladders are of tubular design and hence are light in weight. The rungs of the two ladders extend between, and are connected to, the front and rear side members and serve to space the front side members from the rear side members and also to hold the front and rear members in laterally spaced and rigid relation. The ladders are disposed exteriorly of the fuselage. The upper ends of the front side members *8* are pivotally connected to the longerons *a*¹² of the fuselage framework *a*¹⁰ by hinges *11* and the upper ends of the rear side members *9* of the ladders are pivotally connected to the longerons *a*¹² by hinges *12*. The last mentioned hinges, i. e., the hinges *12*, are connected to the longerons *a*¹² a slight distance in front of the cross member *a*¹³ of the framework of the fuselage. The hinges *11* and *12* are so positioned and arranged that they permit the ladders *1* to swing back and forth between an operative position wherein they extend downwardly and outwardly from the side portions of the fuselage and serve as a medium for permitting persons using the airplane to ascend from the ground and enter the compartment via the doorways *a*⁷ and also as a medium for permitting the occupants of the airplane to descend to the ground in connection with leaving the airplane, and an inoperative position wherein they extend inwards along the bottom portion of the fuselage *a*. The bottom portion of the skin *a*¹¹ of the fuselage is provided with a pair of opposed pockets *13* for receiving the ladders *1* when the ladders are in their inoperative or retracted position. These pockets correspond in shape to the ladders and are of such depth that when the ladders are disposed therein the outer surfaces of the ladders are flush with the portions of the fuselage skin that are adjacent the pockets. By disposing the ladders *1* in the pockets when they are in their inoperative or retracted position aerodynamic drag is reduced to a minimum and the appearance of the airplane when the latter is in flight is materially enhanced. The hinges *11* and *12* extend through holes in the skin (see Figure 4).

In addition to the ladders *1* the ladder structure comprises means controllable from within the compartment *a*⁴ for shifting or swinging the ladders *1* back and forth between their operative and inoperative positions. This means is essentially of simple design and comprises an upper gear segment *14*, a lower gear segment *15* and a pair of links *16* and *17*. The upper gear seg-

ment *14* is disposed midway between the side portions of the fuselage *a* and directly in front of the passenger seat *a*⁶. It is disposed within a two-piece housing *18* and extends transversely of the fuselage. As shown in Figure 2, the gear segment *14* fits within a transverse slot *19* in the floorboard *a*⁹ and is carried for rocking movement transversely of the fuselage by way of a bar type bracket *20*. The latter projects upwardly from and is welded or otherwise secured to the cross member *a*¹³ of the fuselage framework *a*¹⁰. A pivot pin *21* extends through, and projects forwardly from, the upper end of the bracket *20* and extends through a hole in the hub part of the upper gear segment *14*. The segment *14* is of half circle shape and is capable of being rocked by way of a control element in the form of a lever *22*. The latter is fixedly connected to, and projects radially from, a lug *23* on that portion of the hub of the upper gear segment that is diametrically opposite the central teeth of the segment. The two-piece housing *18* consists of front and rear sections and these are so shaped and positioned that they have an arcuate space *24* between them. The lever *22* constituting the control element of the ladder shifting means extends through this space *24* and is adapted to traverse the latter when it is swung in connection with rocking of the gear segment *14*. Swinging of the lever *22* in one direction results in counterclockwise rocking or rotation of the segment *14* and reverse swinging of the lever results in clockwise rocking or swinging of the segment *14*. The gear segment is adapted to be rotated through an arc of 180° only. By reason of the fact that the lever *22* is directly in front of the passenger seat *a*⁶ it is readily accessible or manipulable from within the compartment *a*⁴. The lower gear segment *15* is disposed beneath, and is in mesh with, the upper gear segment *14*. It is located in the space between the floorboard *a*⁹ and the bottom portion of the fuselage skin *a*¹¹ (see Figures 2 and 4). It is rotatably mounted on a pivot pin *25* which extends through, and projects forwardly from, the lower end of a vertically extending bar type bracket *26*. The upper end of this bracket is welded or otherwise fixedly secured to the central portion of the cross member *a*¹³ of the fuselage framework. The pivot pin *25* underlies and extends in parallel relation with the pivot pin *21* for the upper gear segment *14*. The bracket *26* is reinforced against transverse bending by way of a pair of tubular braces *27*. These braces are arranged in V fashion and have their upper ends welded to the central portion of the cross member *a*¹³ and their lower ends welded to the sides of the bracket *26*. The lower gear segment *15* is of half circle shape and has a horizontally elongated hub *28*. The latter has a central hole through which the pivot pin *25* extends and carries a pair of radially extending arms *29* and *30*. The arm *29* extends oppositely to the arm *30* and projects away from the teeth of the segment *15*. The link *16* of the shifting means extends between the outer end of the arm *29* and a bracket *31* on the upper portion of the rear side member *9* of the starboard or right hand ladder *1*. The outer end of the link *16* is pivotally connected to the bracket *31* by way of a clevis *32* and the inner end of the link *16* is pivotally connected to the outer end of the arm *29* by a pivot bracket *33*. The clevis *32* is connected to the link *16* by an externally threaded stem *34* and a lock nut *35* in order that it may

be shifted to and from the link for adjusting purposes. The central portion of the link extends through, and is movable in, a slot 36 which is formed in that portion of the starboard pocket 13 that is designed to receive the rear side member 9 of the starboard ladder. When the gear segment 15 is rotated throughout an arc of 180° in a clockwise direction, as viewed in Figure 2, the arm 29 and the link 16 operate to swing the starboard ladder 7 inwards into its inoperative or retracted position in the starboard pocket 13. When the lower gear segment 15 is reversely rotated throughout an arc of 180° the arm 29 and the link 16 operate to swing the starboard ladder 7 outwards into its operative or extended position. The upper and lower gear segments 14 and 15 are the same in size and are so arranged that 180° rocking of the upper segment by manipulation of the lever 22 effects 180° rotation or rocking of the lower segment 15. The arm 30 projects in the direction of, and past, the teeth of the lower gear segment 15 and is connected by the link 17 to a bracket 37 on the upper portion of the rear side member 9 of the port or left hand ladder 7. The link 17 extends substantially horizontally and embodies a clevis 38 at its outer end whereby it is pivotally connected to the bracket 37. The inner end of the link 17 is connected to the outer or distal end of the arm 30 by a pivot bracket 39. The clevis 38 is connected to the outer end of the link 17 by an externally threaded stem 40 and a lock nut 41 in order that it may be adjusted to or from the link should it be necessary to lengthen or shorten the link as a whole. The central portion of the link 17 extends through and moves within a transverse slot 42 in that portion of the port pocket 13 which receives the rear side member 9 of the port ladder 7. The arm 30 and the link 17 are so arranged that when the lower gear segment 15 is rocked or turned in connection with shift of the starboard ladder 7 into its operative position they operate to shift the port ladder into its operative or extended position. The two links 16 and 17 together with their arms 29 and 30 conjointly shift the ladders outwards into their operative position when the lower gear segment 15 is turned counterclockwise, as viewed in Figure 2, and inwards into their inoperative or retracted position when the gear segment 15 is reversely turned or rotated. A laterally extending stop lug 43 on one corner of the lower gear segment 15 and a laterally extending stop lug 44 on the other corner of such segment serve to limit the lower segment to rotation throughout an arc of 180° only. The stop lug 43 is so arranged that when the lower gear segment 15 is rocked in a counterclockwise direction, as viewed in Figure 3, in order to swing the ladders into their operative position it abuts against the central portion of the bar type bracket 26 and prevents further clockwise rotation of the lower gear segment. When the ladders 7 are in their operative position, as shown in Figure 2, the bracket 33 is above an imaginary straight line running between the pivot pin 25 and the clevis 32 and the bracket 39 is below an imaginary line between the pivot pin 25 and the clevis 38 with the result that any weight on the ladders tends to rotate the segment gear 15 in a counterclockwise direction, as viewed in Figure 2, and this is precluded by the stop lug 43. Because of the arrangement of the links 16 and 17 and the arms 29 and 30 and the location of the stop lug 43 the ladders 7 when in their op-

erative position are locked against inward movement except by clockwise rotation of the lower gear segment 15 and this can only be accomplished by rocking of the upper gear segment 14 through the medium of the lever 22. In other words the various parts of the shifting means are so arranged that the ladders 7 are self-locking or irreversible when in their operative or extended position and can only be retracted by swinging the lever 22 in the proper direction. The stop lug 44 is adapted when the ladders are swung inwards into their inoperative or retracted position to engage the central portion of the bar type bracket 26, as shown in Figure 4, and thus prevent any further inward movement of the ladders.

When the ladders 7 are in their operative position the links 16 and 17, the arms 29 and 30, the two gear segments and the control lever 22 are positioned as shown in Figure 2. In such position of the aforementioned parts the ladders are locked in place and hence they may be stepped on by persons entering or leaving the compartment a^4 in the fuselage. When it is desired to retract the ladders 7 it is only necessary to swing the lever 22 upwards and over throughout an arc of 180°. Such movement on the part of the lever causes the upper gear segment 14 to swing 180° in a counterclockwise direction, as viewed in Figure 2, and the lower gear segment 15 to swing or rotate 180° in a clockwise direction. Such rotation or swinging on the part of the lower gear segment operates through the medium of the arms 29 and 30 and the links 16 and 17 to swing the ladders 7 inwards and upwards into their inoperative or retracted position in the pockets 13. From the foregoing description it is manifest that a 180° swing of the lever 22 in one direction operates to swing the ladders 7 into their operative position and a reverse 180° swing of the lever results in the ladders swinging into their inoperative position within the ladder-shaped pockets in the bottom portion of the fuselage skin a^1 . In the event that the ladders 7 do not properly fit within their pockets when the lower gear segment 15, as viewed in Figure 4, is rotated clockwise to its fullest extent proper adjustment may be made by adjusting the clevises 32 and 38 with respect to their respective links.

The herein described ladder structure is simple in design and effectively and efficiently fulfills its intended purpose. It is light in weight while at the same time it is sufficiently durable and has the requisite strength for its intended purpose. The structure is readily controllable from within the fuselage interior, i. e., the compartment a^4 and cannot be collapsed or retracted when in its operative position by the placement of excessive weight or pressure on the ladders. Due to the fact that the ladders are disposed wholly within the ladder-shaped pockets 13 in the bottom portion of the skin of the fuselage the ladders do not cause any appreciable aerodynamic drag during flight or travel of the airplane A.

Whereas the ladder structure has been described as comprising two ladders it is to be understood that a single ladder on an airplane having a fuselage with a single door is within the purview of the invention. It is also to be understood that the invention is not to be restricted to the details set forth since these may be modified within the scope of the appended claims.

without departing from the spirit and scope of the invention.

Having thus described the invention what we claim as new and desire to secure by Letters Patent is:

1. In a vehicle body having a door closed access doorway and a pocket adjacent the doorway, a ladder structure comprising a ladder pivotally connected to the body and arranged so as to swing back and forth between an operative position wherein it is disposed externally of, and in close proximity to, the doorway and an inoperative position wherein it is disposed in said pocket, and mechanism for shifting the ladder back and forth between its operative and inoperative positions including an element arranged in the body to rock or swing back and forth throughout an arc of less than 360 degrees and a link having its ends pivotally connected to the element and ladder, respectively, said mechanism being designed so that when the ladder is in its operative position it is irreversible or self-locking except by rocking of the element in one direction.

2. In an airplane fuselage having a doorway in one side thereof and an external ladder-shaped pocket in its bottom directly beneath the doorway, a ladder structure comprising a ladder of the same shape as the pocket hinged to the fuselage at a point directly beneath the doorway and arranged so as to swing back and forth between an operative position wherein it extends downwardly and outwardly from the doorway bottom and an inoperative position wherein it is disposed substantially wholly within the pocket, and manually manipulable mechanism for swinging the ladder back and forth between its operative and inoperative positions, consisting of a hand lever in the fuselage interior together with lever actuated gearing and a link between the gearing and the ladder, said mechanism being arranged and designed so that when the ladder is in its operative position it is irreversible or locked against movement except by actuation of the gearing through the medium of the lever.

3. In a vehicle body having doorways in the sides thereof, a ladder structure comprising a pair of ladders associated with the doorways respectively and connected to the body so that they are shiftable back and forth between an operative and an inoperative position with respect to the doorways, and means including an actuating element in the body for conjointly shift-

ing the ladders back and forth between their operative and inoperative positions.

4. In a vehicle body having door closed doorways in its sides and external pockets adjacent the doorways, a ladder structure comprising a pair of ladders associated with the doorways respectively and hinged to the body so as to swing back and forth between an operative position wherein they extend downwardly and outwardly from the doorway bottoms and an inoperative position wherein they are disposed in the pockets, and means including an actuating lever in the body together with lever driven gearing for conjointly swinging the ladders back and forth between their operative and inoperative positions.

5. In an airplane fuselage having doorways in the sides thereof and external ladder-shaped pockets in its bottom portion directly beneath the doorways, a ladder structure comprising a pair of ladders shaped conformably to the pockets and hinged to the fuselage at points directly beneath the doorways so that they may be swung back and forth between an operative position wherein they extend downwardly and outwardly from the bottom portions of the doorways and an inoperative position wherein they are disposed substantially wholly within the pockets, and means including a control element in the fuselage interior for conjointly swinging the ladders back and forth between their operative and inoperative positions.

6. In an airplane fuselage having doorways in the sides thereof and external ladder-shaped pockets in its bottom portion directly beneath the doorways, a ladder structure comprising a pair of ladders shaped conformably to the pockets and hinged to the fuselage at points directly beneath the doorways and so that they may be swung back and forth between an operative position wherein they extend downwardly and outwardly from the bottom portions of the doorways and an inoperative position wherein they are disposed substantially wholly within the pockets, and means for conjointly swinging the ladders back and forth between their operative and inoperative positions, including an actuating lever in the fuselage interior together with lever driven gearing, and arranged and designed so that when the ladders are in their operative position they are irreversible or locked against movement except by movement of the lever:
